INVENTOR. 36
JOSEPH ATHERTON.
BY Hazard & Miller
ATTORNEYS.

UNITED STATES PATENT OFFICE.

JOSEPH ATHERTON, OF GARDENA, CALIFORNIA.

ANTISKIDDING DEVICE FOR VEHICLES.

1,334,644.

Specification of Letters Patent. Patented Mar. 23, 1920.

Application filed May 5, 1919. Serial No. 294,948.

To all whom it may concern:

Be it known that I, JOSEPH ATHERTON, a citizen of the United States, residing at Gardena, in the county of Los Angeles and 5 State of California, have invented new and useful Improvements in Antiskidding Devices for Vehicles, of which the following is a specification.

The objects of my invention are to provide an anti-skidding device for vehicles, the function of which is to prevent the vehicle from slipping dangerously from its line of travel, a further object is to provide an anti-skidding device that is connected 15 flexibly to the vehicle so that it may follow closely the uneven surface of the roadway, another object is to so construct the shoe that it hangs tenaciously to the roadway.

My invention consists of the novel features 20 herein shown, described and claimed.

Figure 1 is a top plan view of the frame and running gear of a vehicle and showing an anti-skidding device embodying the principles of my invention in position for use, 25 the view being taken looking in the direction indicated by the arrow 1 in Fig. 2.

Fig. 2 is a sectional elevation on the line 2-2 of Fig. 1 and looking in the direction indicated by the arrow, and showing the 30 anti-skidding device in operation.

Fig. 3 is a view analogous to Fig. 2 and showing the anti-skidding device out of operation.

Fig. 4 is an enlarged fragmentary sectional detail of the anti-skidding device in 35 planes parallel with Figs. 2 and 3.

Fig. 5 is a bottom plan view of the anti-skidding shoe as seen looking in the direction indicated by the arrow 5 in Fig. 4.

Fig. 6 is a cross section on the line 6-6 of Fig. 4 and looking in the direction indicated by the arrows.

Fig. 7 is a fragmentary view analogous to Fig. 5 and showing the anti-skidding wheels 45 staggered relative to each other, that is the wheels of one row are staggered relative to the wheels of an adjacent row.

Referring to the drawings in detail, bearing brackets 1 and 1' are rigidly secured 50 to the side bars 2 and 3 and extend downwardly near the centers of the side bars. A rock shaft 4 is mounted in the bearings of the brackets 1 and 1', a hand lever 5 is rigidly fixed to one end of the rock shaft 55 4 outside of the side bar 2, a double acting crank wheel 6 is fixed upon the rock shaft

4 just inside of the bracket 1, a link 7 is connected to the crank pin 8 extending one way from the wheel 6, and a similar link 9 is connected to the crank pin 10 extending 60 the same way from the wheel 6 and diametrically opposite the crank pin 8.

Toggle arms 11 and 12 are rigidly secured to the side bar 2 and extend downwardly, second toggle arms 13 and 14 are pivotally 65 connected to the lower ends of the arms 11 and 12, and anti-skidding shoes 15 and 16 are pivotally connected to the lower ends of the second toggle arms 13 and 14. Toggle links 17 and 18 are connected to the toggle 70 arms 11 and 13, and the inner ends of the links 17 and 18 are connected together and connected to the link 7, so that when the rock shaft 4 is operated to rotate the wheel 6 in the direction indicated by the arrow 75 19 the toggle links 17 and 18 are straightened to straighten the toggle arms 11 and 13 and move the anti-skidding shoe 15 downwardly, and so that when the hand lever 5 is operated to move the rock shaft 4 80 in the opposite direction the toggle links 17 and 18 are bent upon the joint to swing the toggle arm 13 upwardly and raise the anti-skidding shoe 15.

In a like manner, the toggle links 20 and 85 21 are connected to the toggle arms 12 and 14 and connected together and connected to the link 9, so that when the hand lever 5 is operated the anti-skidding shoes 15 and 16 go up and down simultaneously. 90

In a like manner the anti-skidding shoes 22 and 23 are connected to the side bar 3 and to the rock shaft 4 through the links 24 and 25 and the double acting crank 26 for simultaneous operation with the anti-skidding shoes 15 and 16. 95

Referring to Fig. 4, the links 7, 17 and 18 are made to yield under compression so that when the anti-skidding shoe 15 is running upon uneven ground the shoe may yield 100 to the unevenness of the ground. The link 7 consists of a rod 27, a barrel 28 connected to the rod by a pin 29, a web 30 extending across the center of the barrel, a rod 31 slidingly mounted through the web 30, a head 32 upon the rod 31 to engage the web and limit the expansion of the link, a spring 33 around the rod 31 against the opposite side of the web 30 from the head 32, and a spring seat 34 upon the rod 31 against 105 the spring; so that under compression the spring 33 may give to shorten the link 7, 110

The links 17, and 18 are constructed in the same way and the anti-skidding shoes 16, 22 and 23 are mounted to yield in the same manner as the shoe 15.

5 Referring to Figs. 4, 5 and 6, the details of the anti-skidding shoe 15 are as follows:

The body or frame of the shoe comprises a flat plate 35, side walls 36 and 37 extending downwardly from the sides of the 10 flat plate 35, end walls 38 and 39 extending downwardly from the ends of the plate 35, and runners 40 and 41 extending forwardly and backwardly from the side walls 36 and 37. A bearing bracket 42 is connected to 15 the center and top of the plate 35, and the lower end of the toggle arm 13 is connected to the bearing bracket 42 by a pin 43. Reciprocating plates 44, 45, 46 and 47 are mounted crosswise in the chamber 48 20 rounded by the walls 36, 37, 38 and 39, stud bolts 49 are fixed in the plates 44, 45, 46 and 47 and extend slidably through the plates 35, and expansive coil springs 50 are placed upon the stud bolts 49 between the 25 plates 44, 45, 46 and 47 and the plate 35 the tensions of the springs being exerted to hold the plates 44, 45, 46 and 47 yieldingly downwardly and so as to allow the plates to yield upwardly.

30 Each plate 44, 45, 46 and 47 is provided with a series of toothed wheels 51, each wheel being independently mounted in bearings 52 extending downwardly from the plates. Normally the wheels 51 extend below the lower edges 53 of the side plates 35 and 37.

When the hand lever 5 is operated to lower the anti-skidding shoes 15, 16, 22 and 23, as in Fig. 2, the toothed wheels 51 will 40 engage the surface of the ground, ice, or pavement and hold the vehicle from skidding sidewise.

The wheels 51 mounted on one shaft may be arranged in staggered relation to the 45 wheels 51 on the shaft adjacent to the first shaft, so that greater bearing surface is pro-

vided to prevent the skidding of the automobile laterally.

Various changes may be made without departing from the spirit of my invention as 50 claimed.

I claim:

1. An anti-skidding device for vehicles comprising a rock shaft mounted transversely of the vehicle having face plates 55 at the outer ends of the shaft, the face plates carrying two wrist pins on each disposed diametrically, brackets fixed to either side of the vehicle frame backwardly of the rock shaft and extending downwardly toward the 60 ground, other brackets fixed to the vehicle frame forwardly of the rock shaft and extending downwardly toward the ground, arms pivotally connected to the lower ends of the four brackets, shoes pivotally connected to the lower end of the arms, the shoes comprising a housing carrying a set of 65 flexibly mounted rollers, toggles connecting pivotally with the brackets, other toggles connecting pivotally with the arms, reach rods connecting with the free ends of the toggles and connecting with the wrist pins on the face plates, the toggles and the reach rods having springs so disposed within their structure as to form a flexible connection 70 between the rock shaft and the shoe, and a lever for operating the rock shaft.

2. In an anti-skidding device for vehicles, an anti-skidding shoe comprising a casing having means for connecting pivotally with 80 a rock arm, bearing members within the casing adapted to rotatably carry rollers and having upwardly extending stems adapted to be slidably mounted in holes in the top of the casing, springs mounted upon the stems between the top of the casing and the bearing members, and nuts upon the stems for holding the bearing members against the pressure of the springs.

In testimony whereof I have signed my 90 name to this specification.

JOSEPH AATHERTON.
